Primary Examiner — Jasmine Mlinarcik*Assistant Examiner* — Victoria A. Rielly(74) *Attorney, Agent, or Firm* — QuickPatents, LLC; Kevin Prince(57) **CLAIM**

The ornamental design for a hair bow clip holder, as shown and described.

DESCRIPTION

FIG. 1 is a perspective view of a hair bow clip holder, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof; and,

FIG. 5 is a bottom plan view thereof.

The broken lines showing hair bow clips in FIG. 1 depict environmental matter and form no part of the claimed design. The remaining broken lines represent stitching, and are part of the claimed design.
